(57) **CLAIM**

The ornamental design for a watch, as shown and described.

DESCRIPTION

FIG. 1 is a top, left front perspective view of a watch showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is a top, left front perspective view, shown in use. The structural features depicted by broken lines in the drawings have been shown for the purpose of illustrating portions of the watch that form no part of the claimed design. The hand and arm portion depicted by broken lines in FIG. 8 has been shown for the purpose of illustrating environment that forms no part of the claimed design.
